CLAIM

The ornamental design for a load controller, as shown and described.

DESCRIPTION

FIG. 1 shows a front perspective view of a load controller. FIG. 2 shows a rear perspective view of the load controller. FIG. 3 shows a front perspective view of the load controller with its cover in an opened position.

FIG. 4 shows a top view of the load controller.

FIG. 5 shows a front view of the load controller.

FIG. 6 shows a rear view of the load controller.

FIG. 7 shows a left side view of the load controller.

FIG. 8 shows a right side view of the load controller; and,

FIG. 9 shows a bottom view of the load controller.

The broken lines in the figures depict portions of the load controller that form no part of the claimed design.

1 Claim, 9 Drawing Sheets
